(57) CLAIM

The ornamental design for a food collection bag, as shown and described.

DESCRIPTION

FIG. 1 is a top front perspective view of a food collection bag, showing my new design;

FIG. 2 is a front elevation view thereof;

FIG. 3 is a rear elevation view thereof;

FIG. 4 is a left-side elevation view thereof, the right-side elevation view is a mirror image thereof;

FIG. 5 is a top plan view thereof; and,

FIG. 6 is a bottom plan view thereof.

The evenly sized broken lines shown in the drawings depict portions of the food collection bag that form no part of the claimed design.

The unevenly sized broken lines shown in the drawings depict the bounds of the food collection bag that form no part of the claimed design.

1 Claim, 4 Drawing Sheets
